UNITED STATES PATENT OFFICE.

GEORGE W. KING, OF EAST ORANGE, NEW JERSEY.

DESIGN FOR A SPOOL OR TUBE HOLDER.

SPECIFICATION forming part of Design No. 29,436, dated October 4, 1898.

Application filed September 9, 1898. Serial No. 690,606. Term of patent 7 years.

To all whom it may concern:

Be it known that I, GEORGE W. KING, a subject of Her Majesty the Queen of Great Britain, residing at East Orange, in the county of Essex, State of New Jersey, have invented and produced a new and original Design for a Thread Spool or Tube Holder, of which the following is a specification, reference being had to the accompanying drawing, forming part thereof.

As shown in the drawing, which illustrates a perspective view of my new spool or tube holder, the design consists of a vertically-arranged standard *a*, rising from a base *b* and having a loop-shaped portion *c* extending

laterally from one side thereof adjacent to its upper end. In the outer side of the loop *c* are openings or eyes *d d*, and on the standard opposite these eyes are pins *e e*, which extend laterally from the standard in line between the sides *c' c'* of the loop *c*.

Having thus described my invention, what I claim as new, and desire to secure by Letters Patent, is—

The design for a spool or tube holder, substantially as herein shown and described.

GEORGE W. KING.
